DESIGN FOR A LEG REST

Florence S. Weill, New York, N. Y.

Application April 3, 1941, Serial No. 100,116

Term of patent 14 years

To all whom it may concern:

Be it known that I, Florence S. Weill, a citizen of the United States and a resident of New York city, in the county of New York and State of New York, have invented a new, original, and ornamental Design for a Leg Rest, of which the following is a specification, reference being had to the accompanying drawing, forming part thereof, and in which:

Fig. 1 is a top plan view of the leg rest in extended position, showing my new design,

Fig. 2 is a side elevational view,
Fig. 3 is an end elevational view, and
Fig. 4 is a perspective view of the leg rest in folded position.

I claim:
The ornamental design for a leg rest, substantially as shown.

FLORENCE S. WEILL.
